TRAILER

Andrew J. Charles, Jackson Center, Ohio

Filed Sept. 9, 1957, Ser. No. 47,673

Term of patent 14 years

(Cl. D14—3)

The essential features of my design reside in the portions shown in full lines.

I claim:

The ornamental design for a trailer, as shown and described.
